DESIGN FOR A CUPBOARD

John R. Morgan, Oak Park, Ill., assignor to Sears, Roebuck and Co., Chicago, Ill., a corporation
of New York

Application November 27, 1936, Serial No. 66,146

Term of patent 3½ years

To all whom it may concern:

Be it known that I, John R. Morgan, a citizen of the Republic of Guatemala, residing in Oak Park, in the county of Cook and State of Illinois, have invented a new, original, and ornamental Design for a Cupboard, of which the following is a specification, reference being had to the accompanying drawing, forming a part thereof.

Fig. 1 of the drawing is a perspective view of a cupboard, embodying my new design and showing one side thereof.

Fig. 2 is a similar view showing the other side thereof.

I claim:

The ornamental design for a cupboard, as shown.

JOHN R. MORGAN.
